COMBINED SPECTACLE, SOAP, AND TISSUE CASE

George Albert Combridge, Los Angeles, Calif.

Application August 9, 1954, Serial No. 32,159

Term of patent 14 years

(Cl. D57—1)

FIG. 1.

FIG. 2.

FIG. 3.

Fig. 1 is a front perspective view of a combined spectacle, soap, and tissue case showing my new design, the top cover being shown in open position;

Fig. 2 is a front perspective view thereof turned upside down, the bottom cover being shown in open position; and

Fig. 3 is a transverse cross-sectional view thereof, the top and bottom covers being shown in closed position.

The rear of the case not shown is plain.

I claim:

The ornamental design for a combined spectacle, soap, and tissue case substantially as shown and described.
